UNITED STATES PATENT OFFICE.

FRANK HONIG, OF OAK PARK, ILLINOIS, ASSIGNOR TO CYCLO CORPORATION, OF CHICAGO, ILLINOIS, A CORPORATION OF ILLINOIS.

WIRE DRAWING AND TAKE-UP METHOD.

Application filed February 27, 1924. Serial No. 695,477.

This invention relates particularly to a continuous wire-drawing method in the sense that the drawing of the wire need not be interrupted at times when the filled spools, or the coils of desired size, are to be removed from a point where they are formed during the wire-drawing operation.

The primary object is to provide a non-stop wire-drawing process, that is to say, a drawing process which need not be interrupted during the life of the dies, and which enables a uniform drawing tension to be exerted upon the wire, notwithstanding the formation of the finished wire into any desired number of coils.

The present invention contemplates drawing wire through one or a series of dies and forming the wire into any desired number of coils and discharging, or permitting the discharge of the coils, from time to time, without interrupting the wire-drawing operation.

A further object of the improved process is to provide for drawing wire through a graduated series of reducing dies in such a manner as to take care automatically of variations in the rates of drawings of the several drawing capstans, due largely to variations in the wear upon the dies, or due to variations in the physical characteristics of different lengths of the same wire passing through the dies. In this respect, the improved process will take care of the variations which occur in practice within predetermined limits, and when these limits have been reached, due to wear of the dies, or for other reasons, it becomes necessary to stop the operation and substitute other dies.

Both objects are attained by employing the wire-drawing capstans as a means for winding the wire in reverse direction, as it discharges from the capstans. The first-mentioned object is accomplished by causing the last capstan to form a succession of coils, the coils being shifted away or removed from the coil-forming zone, at suitable intervals. The second-mentioned object is accomplished by drawing upon the reversely wound coils of wire formed by one capstan as a source of supply for the next die and capstan. The first-mentioned object may be accomplished in a practical way by means of suitable take-up mechanism for receiving wire from the last wire-draw-

ing capstan and enabling the coils or spools of wire to be discharged, from time to time, without interrupting the wire-drawing operation. The second-mentioned object may be accomplished in a practical manner 60 by associating storage-drums with the wire-drawing capstans, and utilizing each storage-drum as a source of supply for the succeeding die and capstan. The storage-drum is independent of the wire-drawing capstan 65 in the sense that it is capable of independent rotation, and in the transfer of the wire from a wire-drawing capstan to its associated storage-drum, the wire is wound, in a reverse direction, on the storage-drum, and 70 thus the wire on the storage-drum is connected by a loop with the wire on the adjacent capstan, and this loop may travel around the axis of the capstan to any extent which may be necessary. 75

The improved process may be described conveniently in connection with one form of apparatus suitable for the practice of the invention. Such a form of apparatus is illustrated in the accompanying drawings, 80 in which—

Figure 1 represents a plan view of a machine adapted to the practice of the improved process; Fig. 2, a section taken as indicated at line 2 of Fig. 1; Fig. 3, a 85 broken plan section showing a portion of the take-up mechanism; and Fig. 4, a broken vertical sectional view showing a slight modification of a shield or guide associated with a capstan. 90

In the machine illustrated, A represents a frame or bench which may be of any suitable construction; B, C, D, a series of parallel shafts upon which are rigidly secured, respectively, the wire-drawing capstans B', 95 C', and D', B² and C², storage-drums associated, respectively, with the capstans B' and C'; E, takeup mechanism, or coil receiving and discharging mechanism equipped with a plurality of reels, preferably three in number, two of the reels designated E' and E² being shown in Fig. 1, these reels being mounted on a carrier E⁴ 100 supported and adapted to be periodically moved by a shaft E⁵; F, control mechanism through the medium of which the carrier E⁴ is rotated one-third of a revolution at suitable intervals; and G, a coil-holder which serves to hold rod-coils, or coils of the stock 105 which is to be drawn. 110

The frame A is shown as in the form of a hollow bed and inasmuch as the storage-drums and the reels of the take-up mechanism are successively offset with relation 5 to each other from one end of the machine to the other, the frame of the machine also preferably is stepped or suitably offset laterally correspondingly, as appears from Fig. 1.

10 The shaft B is shown equipped with a driving gear or pulley 1, through the medium of which power is applied. The shafts B, C and D are, in the illustration given, geared together to move at suitable speed- 15 ratios by means of chain-belts 2 and 3. The shafts of the capstans should be positively geared together, and the gear-ratio should be such as to take care of the successively increased rates of speeds at which 20 the capstans operate to enable them to receive and discharge the wire as it comes from the successive reducing dies.

It may be stated here that in threading up the machine, suitable turns of the wire 25 are taken about the storage-drums and the gear-ratios should be such that a given storage-drum will receive from its associated capstan somewhat more wire than it delivers to the next die in the normal operation of 30 the machine. Thus, the storage-drum will tend to increase the number of coils stored thereon during normal operation of the machine. This increase need not be large, however, and in practice may be a little 35 greater than is necessary to supply the next succeeding die during its life. When, however, the succeeding die becomes so much worn that it tends to deplete the storage on the drum which constitutes its source of supply, this fact will become evident to the operator, and will indicate the necessity of renewing the die. The movement, or lack of 40 movement of the loop of the wire between a capstan and its associated storage-drum will serve to indicate to the operator the manner 45 in which the dies are functioning.

The construction of the capstans and the associated storage-drums will be understood 50 from Fig. 2. Thus, the capstan B' is shown keyed to the shaft B. The capstan is provided preferably with a cylindrical surface 4 upon which is wound any desired number 55 of convolutions of wire 5. The drum B² is journalled on an extension of the shaft B and is disposed adjacent the delivery end of the capstan B'. The drum is provided with a cylindrical surface 6 which is adapted to receive the coils of wire, and is provided also with a sloping annular lateral wall 7 whose inner circumferential edge 60 embraces the outer end of the capstan B'. The frame A of the machine supports a shield 8 which is carried by laterally extending posts 9. The shield 8 has an annular sloping wall 8^a which is separated from

the wall 7 by a narrow space 10; and the outer circumferential edge of the shield 8 is provided with an annular flange 8^b which projects over the inner flange 11 of the storage-drum B². 70

The capstans are equipped with suitable gripping devices for causing convolutions of wire to be gripped upon the capstans, so that the capstans will serve to continuously form new convolutions thereon and 75 discharge the final convolutions from the capstans and thus deliver the wire to the storage-drums, or to a reel of the take-up mechanism, as the case may be. In the illustration of the machine which is now 80 being described, the gripping device associated with each capstan comprises spring tensioned arms equipped preferably with rollers which bear on the convolutions of wire on the capstans. 85

Again referring to the form of machine now being described, the gripping device associated with each capstan comprises three spring held presser-arms 12 (one shown) 90 which are preferably equipped with rollers 12^a which bear on the convolutions of wire. As shown in Fig. 3 each arm 12 has a hub portion 12^b which is pivotally mounted in or on a boss 13 carried by the shield 8. In the illustration given, the hub or shaft of 95 the arm is made hollow and contains leaf springs 14 which are connected at one end with the bottom of the bore in the boss 13 and at the other end with the hub 12^b, so that the leaf springs will serve as torsion 100 springs tending to hold the pressure-roller 12^a against the convolutions on the capstan. The exact details of construction are not 105 important, as any suitable spring may be employed to hold the pressure-roller against the convolutions of the capstan. It is important, however, to grip the convolutions at at least three points on the circumference 110 on the capstan, and it is likewise important to have the tension of the several rollers approximately equal. The effect of the 115 pressure-rollers is to cause the convolutions of wire to grip the capstan throughout the extent of the surface of the capstan enveloped by the convolutions. When the device functions normally this action occurs, and buckling of the convolutions at points between the pressure-rollers ordinarily does not occur. In some cases, however, as when 120 one is dealing with a very fine or very pliable wire, or when the tensioning of the rollers is not accurate, there is a tendency for some convolution or convolutions to buckle between the rollers. Where this occurs, the difficulty may be obviated by employing the expedient shown in Fig. 4 125 which will be described later.

Each capstan preferably is provided with a flange 15, adjacent to which the first convolution of wire received on the capstan is 130

- located; and the gripping device preferably is arranged so that several convolutions of wire adjacent or near the flange 15 will be gripped, as will be understood from Fig. 2.
- 5 Experience has demonstrated, however, that in drawing some sizes and kinds of wire, it is not necessary to grip a large number of convolutions in order to effectually draw the wire onto and feed it from the capstan.
- 10 In the illustration given, a series of three reducing dies 16, 17 and 18, of successively reduced diameter, is shown. Guide wheels 16^a, 17^a, and 18^a, respectively, guide the wire to these dies. The wire passes from the 15 stock G' through the die 16 to the capstan B', from the capstan B', by a reverse winding, upon the storage-drum B², from thence to the die 17, thence to the capstan C', thence, by reverse winding, to the storage- 20 drum C², thence through the die 18 to the capstan D', and thence, by reverse winding, to one of the reels with which the carrier E⁴ is equipped.
- 25 By way of example, it may be stated that the wire is taken from the capstan B' through the annular inclined passage-way 10 onto the storage-drum B², the winding being reversed, however, on the drum B². Thus, the wire forms a loop 5^a between the 30 capstan and the storage-drum. For convenience in threading the wire, the shield 8 preferably is provided with a slot 19 which is cut transversely through the shield, the slot preferably extending diagonally.
- 35 As the capstan progressively forms and discharges convolutions, the discharged wire passes through the annular space 10 onto the storage-drum B², and is taken from the underside of the storage-drum to the next 40 succeeding die. Thus, as the wire is drawn through the next die, the storage-drum B² rotates in a direction counter to the direction of rotation of the capstan B'. The storage-drum is journalled on a reduced extension 20 of the shaft B and is held thereon by lock nuts 21, by means of which a certain amount of friction may be applied, if desired.
- 45 By way of example, the capstan B' rotates at such speed with relation to the rotation of the next succeeding capstan C' that additional convolutions (beyond those initially placed on the drum B² in threading the machine) will very slowly accumulate on the 50 storage-drum. In other words, the machine is so geared that normally, and under perfect operating conditions, the capstan will deliver to the storage-drum, wire at a slightly greater speed than it is taken from the 55 storage-drum to meet the requirements of the next succeeding capstan. Under these conditions, the loop 5^a will advance clockwise very slowly, assuming the capstan to be rotating clockwise. As the next succeeding 60 die wears, however, the wire may be payed out from the storage-drum B² at a faster rate than would be required by the unworn die. Under such conditions, the rate of advance of the loop 5^a will be gradually lessened, and finally the loop will cease to advance. This 70 will occur at the moment when the wire payed out from the drum B² equals the amount received by the drum. When this condition occurs, the operator is instructed to renew the die. The machine can operate 75 somewhat longer, but eventually, if the die is badly worn, all of the wire stored on the storage-drum will be removed therefrom, and the wire will be broken unless the machine be stopped. 80
- 85 In the case of the last wire-drawing capstan, that is the capstan D', one of the take-up reels receives the wire as it is delivered from the capstan. In this case, the take-up reel remains stationary, or substantially so, while it is being filled. The capstan D' has associated therewith a gripping device comprising suitable pressure members. In the illustration given, spring pressed arms equipped with rollers adapted to bear on 90 convolutions of wire on the capstan are employed, the same as in connection with the other capstans. Also, a shield 8 is employed, the same as already described in connection with the other capstans. There is in this case, (Fig. 3) an inner shield, or guide plate, in the form of an annular inclined wall 22 mounted on arms 23 radiating from a hub 24 which is journalled on the end of the shaft D and held in place by a nut 25. The spider thus described is capable of rotating with relation to the shaft D. There is between the wall 22 and the shield 8 an annular passage 26 through which the wire can pass to be deposited on the reel. The wire forms a loop in passing from the capstan to the reel and is wound on the reel in a direction the reverse of that on the capstan. As the wire is wound on the reel, the loop in the wire advances around the center which corresponds with the center of the shaft D, but, of course, does not travel forwardly at the same speed as the peripheral speed of the capstan. The stiffness of the wire is sufficient to cause the wire itself to act, more or less, as an arm tending to deliver the wire in enlarging convolutions to the reel. This same sort of action occurs in the delivery of the wire from the other capstans to the storage-drums. In the case of the reel, the diameter preferably is approximately twice the diameter of the capstan D'. The diameter of the reel may be any desired multiple of the reel, however. It is desirable, nevertheless, to make the diameter of the reel slightly less than twice the diameter of the capstan. When this is done, the reel will not rotate, except as the diameter is increased by a layer or layers of wire on the reel. The reel may then be rotated by the 100 105 110 115 120 125 130

wire sufficiently to compensate for the increase in diameter.

The carrier shaft E^5 is journaled in suitable bearings 27 and 28 with which the frame is provided. The shaft is automatically rotated, from time to time, by means which will be described presently. The carrier E^4 is in the form of a hub 29 pinned to the shaft E^5 and equipped with radial arms 30 provided with bearings 31. Through the bearings 31 extend the shafts 32 of the reels. The outer ends of these shafts are equipped with lock nuts 33, which may be adjusted to regulate the friction, if desired. Each shaft 32 is provided with bores equipped with tension springs 34 whose inner ends are connected with a hub portion of a spider 35 which is adapted to serve as a coil-stripper. The hub portion of the spider is equipped 20 with a central guide pin 36 which extends freely through a central bore in the shaft 32.

Each reel is provided at its outer end with a flange 37, and the spider 35 is provided with a flange 35^a forming a part of a ring 35^b which is adapted to slide on the outer surface of the reel (Fig. 3). The reel is provided with slots 38 through which extend portions 35^c of the spider, these portions connecting with the ring 35^b.

The reels may be provided, if desired, with retaining-fingers (not shown) adapted to be sheathed or retracted when the coil is to be discharged from the reel.

In Fig. 1, the reel E' is shown in the loaded position, while the reel E^2 is in position ready to be moved through the arc in which the stripper is actuated to discharge the coil 37^a. The coil is shown secured against unwinding by means of ties 38^a. In

this position, the third reel E^3 is disposed below the plane of the shaft E^5 and is ready to be moved to the loading position when the carrier is again actuated. The strippers are actuated by a segmental cam 39 which

45 is in position to engage the plungers 36 as they are, in turn, carried past the cam. When the coil drops from the reel, it may be received by a suitable runway (not shown). The wire between the loaded reel and the freshly positioned reel may be cut, at leisure, when the carrier E^4 is at rest.

The control mechanism F may be of any suitable construction. Such mechanism may be adapted to actuate the shaft E^5 periodically and turn the carrier E^4 one-third of a revolution at each actuation. If desired, means may be provided for regulating the length of the period between actuations of the carrier, so that coils of any desired size 60 may be deposited upon the reels.

65 The holder G for the coils G' of rod is shown as adapted to support the coils on edge. The holder is provided with a conical end 40 which has a central perforation through which the stock is drawn from the

interior of the adjacent coil. The rod passes beneath a roller 41, and thence up over the roller 16^a and to the die 16. The final, or outer end of the first coil of rod is connected with the inner end of the next coil 70 of rod, as indicated at 42. The ends of the coils may be welded together, if desired. The coil does not rotate while the wire is being withdrawn; hence it is possible to weld successive coils together conveniently 75 by a suitable electric welding machine.

Any suitable form of gripping device may be employed for causing the convolutions on the capstans to grip the respective capstans. Where gripping rollers are employed, as described, there may be, at times, a tendency for a convolution to bulge between a pair of gripping rollers. This may occur because of some inequality of tension, because of some variation in friction at some point, or because of some variation of stiffness of the wire. The tendency to buckle, in any case, may be overcome by providing a guard about the capstan in the manner illustrated in Fig. 4. In the modification shown in Fig. 4, H represents a capstan and I represents a shield or dished guide plate which corresponds with the shield 8, previously described. The member I has the inner end of its inclined wall provided with a flange 44 which encircles the capstan rather closely, but without contacting normally with the convolutions of wire on the capstan. The flange 44 is divided into segments by slots 44^a which correspond with the locations of the presser-rollers. In other words, the presser-rollers can extend through the slots and engage the convolutions of wire on the capstan. In case of incipient buckling of convolutions, the surrounding wall afforded by the flange 44 will serve to prevent serious buckling and facilitate the restoration of the normal condition in which the convolutions tightly grip the capstan.

Describing the operation of the machine briefly, the rod or stock which is to be reduced is drawn from a source of supply which may be constantly renewed by welding successive coils together. Thus, the wire passes from the first coil G' through the die 16 to the capstan B' , thence through a loop to form reverse convolutions on the storage-member B^2 , thence from the bottom of the storage-member B^2 over the pulley 17^a and through the die 17 to the capstan C' , thence through a reversing loop onto the storage-drum C^2 , thence from the bottom of the drum C^2 over the pulley 18^a through the die 18 to the capstan D' , and thence through a reversing loop onto that reel of the take-up mechanism E which happens to be in receiving position. The capstans are positively driven, the second capstan in the succession being driven normally at a slightly 125 130

slower speed than would be requisite to take the wire from the drum B^2 at the same rate that it is deposited thereon, and the third capstan in the succession being driven at a 5 slightly slower speed than would be requisite to take the wire from the drum C^2 as fast as it is deposited thereon. Under these conditions, and assuming the dies to be of the correct diameter and unworn, the 10 loops, through which the wire passes in being transferred from the capstans to the storage-drums, advance slowly in the direction of rotation of the capstans. Should the die 17, for example, become unduly 15 worn, wire would be taken more rapidly from the storage-drum B^2 than at the outset, and the loop of wire advancing about the capstan B' would have its advance gradually retarded. Finally the loop would 20 reach a point where it would become stationary, and this would be an indication to the operator that the die 17 required renewing. The operation would, at the proper time, cut the wire between the source of 25 supply and the first die, and allow the machine to clear itself from wire. New dies would then be substituted, and the wire would be rethreaded through the dies and about the capstans and storage-drums.

30 The final capstan, D' of the series, delivers the wire to a reel which preferably is of such diameter that it will have little or no rotation at the outset. The reel is free, however, to rotate on its axis, if necessary, suitable 35 friction being applied, if necessary, to retard the rotation. If we assume the receiving reel to stand still, it, in effect, has a relatively rearward rotation with respect to the capstan D' . In any event, the capstan D' 40 runs ahead of the reel and the loop of wire between the capstan and the reel causes the wire to be carried about and deposited on the reel.

At suitable times, the control mechanism 45 F operates to cause the carrier of the take-up mechanism to rotate one-third of a revolution. When the carrier of the take-up mechanism rotates, it carries a newly filled reel away from the receiving position and brings 50 a fresh reel into the receiving position. The wire may be severed between the reels at leisure, or it may be left connected, assuming that the reel is properly proportioned so that it need not rotate, or will have little rotation, 55 if any, while the convolutions are being deposited on the receiving reel.

With reference to the storage-drums, it 60 may be stated that where a storage-drum is substantially twice the diameter of the associated capstan, the drum may be held still and the capstan will then operate to draw and deliver the wire through a loop which will advance about the axis of the capstan and the wire will, at the same time, expand 65 and be deposited, in reverse revolutions, on

the stationary drum. Under such conditions, the expanded coils on the drum are stationary. If the drum be made of a diameter substantially less than twice the diameter of the capstan, it will not take all of 70 the wire delivered to it without rotating in a reverse direction, or without the coil rotating on the drum. The effect of rotating the storage-drum contra-clockwise while the capstan rotates clockwise, is to retard the advancing movement of the loop. It would be possible to make the storage-drum less than twice the diameter of the capstan for the reason that the storage-drum is rotated 75 contra-clockwise as the wire is drawn therefrom to the next succeeding capstan. In the case of a receiving-reel at the take-up mechanism, the drum should be substantially twice as large as the capstan, or some multiple of the capstan, if it be desired to have 80 the enlarged convolutions become stationary, so that the reel need not rotate.

The machine illustrated enables a novel method of drawing and handling wire to be employed. In this method, a predetermined 85 number of convolutions of wire are gripped on a positively driven capstan, and the wire beyond the gripping convolutions passes through a loop and is formed into reverse convolutions of enlarged diameter. The 90 loop serves the function of a planetary arm and the winding into reverse convolutions is thus effected by the capstan. The receiving-drum, or reel, is a vehicle for receiving the reversely wound convolutions. The expansion of the convolutions to proper size in 95 effect renders the convolutions nonrotating, or substantially so. That is, this is the normal effect, notwithstanding that in the case of the storage drums B^2 and C^2 the drums are reversely rotated by the wire passing to the succeeding capstans, while in the case of the receiving-reel, the reel may be stationary, or substantially non-rotating, while the 100 convolutions are formed thereon. In any 105 event, the rotation of the reel may be so slow as to permit a newly filled reel to be removed from the receiving point and a fresh reel brought into position without stopping the convolution-forming process. This enables 110 a continued, or uninterrupted wire-drawing process to be practiced within the limits of the life of the dies. It may be stated here 115 that diamond dies may be employed, or dies of great longevity may be provided by any suitable method.

The improved process of drawing and handling wire serves to make breakages 120 much less frequent, prevents scoring or excessive wear upon the capstans, and enables 125 successive coils to be formed at the take-up mechanism, and discharged from said take-up mechanism, without interrupting the wire-drawing process. In the practice of 130 this process, no momentary stoppage of the

drawing action of the capstans occurs, and this is an additional reason why breakage of the wire is largely, if not wholly, obviated by the improved process.

5 If we consider the capstan D' and the operation of the take-up mechanism, it will be understood that the capstan operates to pull or draw wire onto itself and deliver the wire into reversely wound convolutions. So 10 far as this action is concerned, it makes no difference whether the wire is drawn from a finishing die, or from some other source of supply. Thus, the take-up mechanism is capable of pulling or drawing wire from 15 any desired source. It may, for example, take wire from a reel and rewind it into a plurality of coils. It may serve to draw wire through an annealing furnace, or through a coating bath, and then rewind 20 the wire into smaller coils. As another example, the take-up mechanism would serve to take wire from a very large spool, or coil, and rewind it into a plurality of coils, or onto a plurality of spools. While, in the 25 illustration given, the wire is delivered from the capstan D' and reversely wound directly on the cores, this is to be considered as illustrative only. Obviously, the winding of the wire on spools, carried by the reels, would 30 be the same in principle, or the reels themselves may be regarded as removable spools.

The novel process and machine are well adapted to the production of large coils of comparatively heavy wire, enabling the 35 coils to be of such size and weight as to enable them to be conveniently handled. However, the process and machine are applicable to the drawing of wire of smaller sizes, where the coils may nevertheless be 40 formed of any desired weight.

The present invention constitutes a modification of the process set forth in my application No. 695,478, filed of even date herewith. A machine well adapted to the practice 45 of the process described in the present application is fully shown and described in my pending application No. 689,651, filed January 31, 1924.

The foregoing detailed description has 50 been given for clearness of understanding only, and no unnecessary limitations should be understood therefrom, but the appended claims should be construed as broadly as permissible in view of the prior art.

55 What I regard as new, and desire to secure by Letters Patent, is:

1. In wire handling, the method which 60 comprises winding wire continuously on a capstan and simultaneously discharging wire from the capstan and forming it into a loop and utilizing the action of the capstan to reversely wind the discharging wire into convolutions.

2. In wire handling, the method which 65 comprises winding wire continuously on a

capstan and simultaneously discharging wire therefrom to form a free loop which is caused by the action of the capstan to move about the axis of the capstan and effect reverse winding of the wire as it is discharged from the capstan. 70

3. In wire handling, the method which comprises winding wire continuously on a capstan and simultaneously discharging wire therefrom in a loop-like path and reversely winding the wire from the loop in 75 enlarged convolutions.

4. In the taking of wire from a capstan, the method which comprises causing the wire to describe a loop and then form into 80 enlarged, reversely wound convolutions on an independently revolvable storage-drum.

5. In the taking of wire from a capstan, the method which comprises utilizing a loop 85 of the wire to serve, due to the stiffness of the wire, as a means for effecting reverse winding of the wire which has described a loop in passing from the capstan.

6. In wire handling, the method which 90 comprises maintaining substantially a predetermined number of convolutions on a drawing capstan and taking the wire beyond said convolutions from the capstan and forming reverse convolutions.

7. In wire handling, the method which 95 comprises maintaining substantially a predetermined number of convolutions on a drawing capstan and taking the wire beyond said convolutions from the capstan as enlarged reverse convolutions. 100

8. In wire handling, the method which 105 comprises maintaining substantially a predetermined number of convolutions on a drawing capstan and taking the wire beyond said convolutions from the capstan in enlarged reverse convolutions which normally would be substantially a multiple of a convolution formed on said capstan.

9. In the handling of wire, the method 110 which comprises causing a predetermined number of convolutions of wire to grip the capstan, and taking the wire as it is formed beyond said convolutions in a loop-like course and forming it into reverse convolutions about an axis substantially in alignment with the capstan-axis. 115

10. In handling wire, the method which 120 comprises progressively forming convolutions on a driven capstan and causing a limited number of said convolutions to grip the capstan sufficiently to exert the necessary drawing action, and discharging the wire beyond the gripping convolutions and forming it into a reversely wound coil in alignment with the axis of the capstan. 125

11. In handling wire, the method which 130 comprises progressively forming convolutions on a driven capstan and causing a limited number of said convolutions to grip the capstan sufficiently to exert the necessary

drawing action, and discharging the wire beyond the gripping convolutions and forming it into reverse convolutions about an axis substantially in alignment with the

5 axis of the capstan and maintaining the reverse convolutions as stationary or slowly rotating convolutions.

12. The method of taking wire from capstan to capstan in a wire-drawing operation, 10 which comprises reversely winding the wire as it is taken from one capstan and drawing a supply for the next die and capstan from the reversely wound wire.

13. The method of taking wire from a 15 capstan which comprises unwinding wire from the capstan and forming it into re-

verse convolutions until a coil of desired size results, and then removing said coil without stopping the drawing and reverse winding operations.

20

14. In handling wire, the method which comprises taking the wire through a loop as it comes from a capstan and utilizing the action of the capstan to reversely wind the wire into convolutions, allowing the operation to continue until a reversely-wound coil of desired size is formed, and then shifting the coil thus formed from the forming position, without stopping the reverse convolution-forming action.

25

FRANK HONIG.
